ELECTRICAL SELECTOR SYSTEM

Maurice D. Sarbey, Bay Village, Ohio

Application December 13, 1933, Serial No. 702,267

26 Claims. (Cl. 178—23)

This invention relates to electrical control systems, and particularly to control systems adapted to the conveyance of independent differentiated control pulses over a single channel, each 5 pulse being a complete signal.

An object of the invention is to convey along a single channel a sequence of electrical pulses, each signal pulse being a complete signal adapted to produce differentiated results at a remote 10 receiving point.

Still another object of this invention is to distinguish different signal pulses in terms of the magnitudes thereof for the production of different effects at a receiving point.

A further object of this invention is to initiate 15 at a transmitting point a plurality of signals of different electrical magnitude; to convey the signals along a single channel; and to translate the varying magnitudes into varying responses at a receiving point.

Another object of the invention is to transmit 20 over a single wire circuit a plurality of electrical pulses in sequence, successive pulses having different electrical magnitudes; and to translate the respective magnitudes into predetermined responses at a receiving point.

Another object of the invention is to operate 25 any one of a plurality of devices selectively by means of the electrical magnitude of a signal, the signal magnitude being sufficient to operate a predetermined device and those devices operable by a lesser signal magnitude being prevented from operating by the operation of the predetermined device.

A still further object of the invention is to 30 transmit over a single wire circuit a plurality of electrical pulses of varying electrical magnitude, and to utilize the successive pulses for the selective operation of a plurality of responsive devices 35 respectively operable by predetermined signal magnitudes, and to render inoperable all the responding devices except the one operable by the signal magnitude transmitted.

Another object of the invention is to set up a 40 group of potential responsive devices such that a given potential applied to the whole group will actuate only one thereof.

A further object of the invention is to connect 45 a plurality of electrically responsive devices in parallel to a single circuit for the application simultaneously to all thereof of a plurality of electrical control pulses, the devices being so arranged that some may not be operated by a pulse, others may be operated by a pulse, thereby 50 producing a line of division between those oper-

ated and those not operated, and causing the device operated nearest to the line of division to put out of operation all of the others operated.

Still a further object of the invention is to apply to a single wire a succession of electrical 5 pulses of varying electrical magnitude, to convey the pulses to another point, and there apply the successive pulses in sequence to a plurality of responsive devices, the respective devices being operable by pulses of different magnitude, each 10 device being adapted to put out of operation those devices which are operable by lower magnitude pulses.

Still another object of the invention is to convey over a cable single electrical pulses of non- 15 significant or uniform time duration and of significant electrical magnitude for the conveyance of intelligible signals, which may be utilized for the operation of a printing telegraph.

Another object of the invention is to transmit 20 over a single line a plurality of electrical pulses of non-significant time duration and significant electrical magnitude at low, closely spaced electrical magnitudes, to amplify the electrical magnitudes to higher values and increase the spacings there-between and thereafter to utilize the 25 amplified electrical magnitudes for the operation of predetermined magnitude responsive devices, each different signal magnitude causing the operation of a single predetermined device. 30

Still another object of the invention is to operate a typewriter at a remote point by means of a plurality of single electrical pulses of non-significant time duration and of significant electrical magnitude, each type key being operated 35 by a current pulse of a predetermined magnitude different from the magnitudes required for the operation of all of the other keys.

Still another object of the invention is to operate 40 a printing telegraph device by means of a plurality of electrical pulses, the respective types of the printing telegraph being selected by choice of the magnitude of the electrical pulses transmitted at the sending point.

Still another object of the invention is to transmit 45 digit selecting pulses as for automatic telephone dialing by pulses of predetermined electrical magnitude, each digit being represented by a single pulse of a definite electrical magnitude. 50

Still another object of the invention is to initiate 55 electrical pulses of varying magnitude according to the electrical indication of a photo-cell, to transmit these pulses to a remote point, and to operate a predetermined one of a plurality of

devices according to the magnitude of the electrical pulse initiated by the photo-cell.

Still another object of the invention is to produce a desired mechanical operation, or a plurality

- 5 of operations, at a remote point by the transmission thereto of a single electrical pulse or pulses of a predetermined electrical magnitude, each such operation being obtainable by a single electrical pulse of a different electrical magnitude 10 than that required for the other operations, and to use the mechanical or electrical movements directly or to control electrical or other mechanical functions.

In the prior art of signal conveyance, it has 15 been found convenient to convey control signals in a variety of ways, successive independent pulses being used, such, as for instance, the telegraph code, in which time durations of successive pulses and spacings are utilized for the conveyance of 20 information, and such as the five unit code, in which the presence or absence of pulse at synchronized intervals determines the character of signals conveyed. Both of these methods involve a determination of elapsed time in the course of 25 signal transmission which is often undesirable. Other control circuits require a large number of wires, a separate wire or circuit being provided for each control function. Still other control systems utilize relay chains of various forms in 30 which the relays are actuated in succession according to the duration or sequence of the current pulses controlling them.

The device of this invention provides a simple 35 control system in which the information or control factor is conveyed in terms of electrical magnitude, instead of in terms of time or sequence or relay chains as in the prior art.

Thus the device of this invention provides 40 means by which a given electrical magnitude may be made to convey a given signal, or to control a given operation while a second slightly different electrical magnitude carries a different item of 45 information or effects a different control.

That is, broadly, the device of this invention 45 makes it possible to apply to a given circuit a certain electrical magnitude, which may be a small number of volts, which, when so applied, by the device of the invention, will actuate a given member; and a second slightly different electrical magnitude, a higher or a lower voltage, will actuate 50 a different member; still another voltage will actuate a different device and so on over a range of voltage steps, both the number and size of the steps being determined by the insulation resistance 55 of the system, the current carrying capacity, the characteristics of the component parts, and the other usual electrical factors.

The invention may also utilize, in combination 60 with the voltage responsive devices, an amplifying member adapted to increase the magnitude of electrical values applicable to the device, thereby making it possible to utilize a large number of closely spaced voltage steps at low voltage for transmission, and to increase the magnitude by amplification at the receiving device to insure 65 accuracy of operation.

The device of this invention thus provides, in combination, means for transmitting signals or control impulses in terms of electrical magnitude, and means responsive to the electrical magnitude for the actuation of different signal control devices.

Other objects and structural details of the invention will be apparent from the following

description, when read in connection with the accompanying drawings, wherein:

Fig. 1 is a circuit diagram of a simple signal device embodying the invention.

Fig. 2 is a circuit diagram of a modified circuit 5 embodying the invention, including an amplifying member, shown in conjunction with a cable conductor.

Fig. 3 is a circuit diagram of a device illustrating the invention applied to a radio signal channel.

Fig. 4 is a diagrammatic representation of an embodiment of the invention as applied to the sending and reception of automatic telephone dialing or pulsing signals.

Fig. 5 is a diagrammatic representation of an embodiment of the invention, utilizing a photo-cell for the control or production of the signal voltage.

The present invention utilizes electrical pulses 20 of different magnitudes for the conveyance of the desired control or information signal. A single circuit may be used between the sending and receiving points, over which may be conveyed successive electrical pulses for the successive signal or control functions. These pulses are of different voltages, each desired signal or control operation being represented by a pulse of predetermined different voltage. Such signals are conveniently obtained by the closing of keys connected to different points in a chain of series connected batteries, or from keys connected to successive points on a potentiometer resistance energized from any convenient power source, preferably of direct current. One end of the potentiometer 30 may be connected to ground or to a return wire. The several keys are then connected in parallel to a line wire and serve to transmit over the line wire the desired pulses, controlled in voltage according to the desired signals or actuation to be obtained.

At the remote end of the line wire there is provided a receiving system having a plurality of devices respectively responsive to different voltages, so that a low voltage will actuate one response device, a higher voltage will actuate another, and a still higher voltage will actuate still another, the number of devices, and of different voltages, being determined by the number of signals to be transmitted, or of operations to be 45 obtained.

In view of the fact that a device that is responsive to a given voltage is usually also responsive to higher voltage, the invention provides additional means to prevent the operation of more than one of the voltage responsive devices at one time, whereby the responsive device, which it is desired to actuate by the applied voltage, prevents the actuation of those devices, which are adapted to be actuated by lower voltages.

Simple control system

Of the preferred embodiments of the invention herein illustrated and described, the simplest form of the device is shown in Fig. 1. Referring 65 to this figure, a potentiometer resistance R is provided through which an electrical current is caused to flow by a source of current, which may be a battery B , or may be any convenient power source (a direct current generator, or a rectifier). 70 A plurality of taps are connected to the potentiometer R and lead to the keys K . The other terminals of the keys K are connected to a common lead L , which, in turn, is connected to the line with the positive and negative poles con- 75

nected, as shown. The negative end of the potentiometer is grounded at G, as shown, or may be connected to a return line and, for reasons which will later appear, it must be the negative end. It may be noted that the first of the keys K is not connected at the grounded end of the potentiometer resistance R, but is connected at a point a short distance away, so that the closure of the first key K1 applies a definite voltage between line and ground. Similarly, the closure of key K2 applies a still larger voltage between line and ground and, so on, each key thus applying its characteristic voltage to the line, which voltage may conveniently have values in an arithmetical progression.

At the receiving end the device referred to utilizes a number of gas discharge devices, which number may be the same as the number of keys K at the sending point. While any gas discharge device which has a control element and a circuit responsive thereto and which has such an operating characteristic that the controlled circuit passes substantially no current until the control element has reached a certain predetermined narrow range of electrical potential, and thereafter passes substantially full current, may be employed, the gas discharge devices illustrated are of the type known commercially as "Thyratrons", and consist of an envelope containing a low pressure of vapor, such as mercury, argon, etc., and a plurality of electrodes consisting of cathode, grid and anode. These devices are of the type which show practically no conductance when the grid is more negative than a specific value and pass full current when the potential on the grid reaches or exceeds in the positive direction the specific or critical value peculiar to the device.

If, as illustrated, a hot cathode type of gas discharge device is used, the cathodes of the entire group may be connected in parallel, as is indicated in Fig. 1, and may be energized from any convenient power source such as an alternating current line, (with a transformer to provide the proper voltage).

Another potentiometer RR is provided at the receiving point, which may also be energized by any convenient power source such as a battery BB. It may be noted that the poling of this battery, in common with the battery B at the sending point is of consequence, the positive end of the battery BB being connected to the grounded end of the potentiometer RR. The successive gas discharge devices T1 to T5, inclusive, as shown, are equipped with connections from the respective grids thereof to successive points on the potentiometer RR. It will be noted that the successive points of connection of the grids of the tubes of the gas discharge devices T1 to T5, inclusive, are connected successively at more negative points and, accordingly, the respective grids are biased negatively by higher and higher values. Each device T has in its plate circuit a relay member indicated by the reference characters M1 to M5, inclusive.

Each of the relays M has two pairs of contacts, one pair being normally closed when the relay is unenergized, and the other pair being normally open when the relay is unenergized. In addition, the construction of the relays is such that upon energization of the relay, the first mentioned pair of contacts is opened at once, while the second mentioned pair of contacts is closed only after a brief time delay.

The relays M may be of a solenoid type, as indi-

cated diagrammatically in Fig. 1, in which the prompt opening of one pair of contacts, and closing of another pair of contacts after a brief time delay, is more or less inherent. Alternatively, a standard type of relay may be equipped with contact springs and armatures of different masses, controlled by springs of different tensions, such that one will open quickly, and the other will close after a brief delay because of the necessity of accelerating the heavier armature against a heavier spring tension.

Other types of construction of suitable relays having the above described characteristics will also be obvious. For instance, the effectiveness of the relay may be increased either by the type of winding, the mechanical construction, or by the use of damping rings to obtain the desired delayed action in the latter part of the contact operating stroke. Alternatively, a pair of relays may be utilized, one adapted to open a pair of contacts upon energization with a minimum of time delay, the other adapted to close a pair of contacts after a small time delay. In such a system the second relay may be operated from circuit closing contacts on the first relay.

The several plate circuits of the gas discharge devices T are connected through the windings of the several associated relays to the current supply. The normally closed contacts of each relay carry the current for all of the relays in circuit with gas discharge devices having lower negative biases on the grids in such a way as to open the plate circuits of all the less negatively biased devices when any one operates (except, of course, the lowest biased device, which has no associated device with a still lower bias). This action is apparent from the diagram of connections shown in Fig. 1.

The source of anode power for the system illustrated preferably provides alternating current because of the fact that this gives a cessation of current flow during each cycle (the gas discharge device being unilaterally conductive, current does not flow during the reverse half of the cycle). This is advantageous because of the fact that, if direct current were used with the commercially known Thyratron gas discharge device illustrated, means would be required to interrupt the current flow in the tube, since this gas discharge device does not cease to carry current when the bias upon the grid is returned to its negative value. Obviously if mechanical marginal relays are employed, or gas discharge devices in which the plate current is interrupted when the grid is returned to a negative value, direct current may be used in the controlled or anode circuit without the use of supplemental means for interrupting the flow of current therein. It may be noted that the circuit illustrated is substantially a self-rectifying circuit and each gas discharge device provides its associated relay with rectified current. Because of the requirement that the relay have a fairly steady current in order to complete the delayed latter part of the stroke, the condensers C1 to C5 may be included in the circuit to form with the relay winding a simple smoothing filter.

These condensers may be on the order of one microfarad in size. The size is not critical and the above size is suitable for the ordinary relay. If a different size relay, or one having different characteristics, is utilized, different condensers may be desirable, according to the characteristics of the relay and circuit.

In circuit with the grid of each of the gas discharge devices T, there is provided a resistance

G, the several resistances for the several tubes being indicated at G1 to G5, inclusive. These grid resistors are inserted to limit the grid current, which might otherwise tend to flow when 5 the device becomes conducting. Under such circumstances, the presence of a substantial grid current would cause excess current in the potentiometer RR, and unbalance the bias voltages.

The upper contacts of the respective relays M1 10 to M5, inclusive, may be utilized for the closing of any desired circuits; alternatively, the movement of the relay solenoid plunger may be utilized directly for any mechanical operation or movement within its power or capacity.

15 In the operation of this embodiment of the device, with all of the keys K1 open, no voltage is applied to the common lead L or to the line, and, accordingly, all of the grids of the gas discharge devices T assume the potential set by the 20 points to which they are connected on the potentiometer RR, the relative grid voltages being determined by the relative connection points, and the actual voltages being determined in addition by the voltage of the battery BB. In normal non-operated condition, all of the biases applied to the 25 grids of the several gas discharge devices are more negative than the critical point, and, accordingly, none of the devices pass current; all of the relays M are unenergized, and all of their lower contacts are closed, permitting the application 30 of voltage from the anode power supply source to the respective anodes of the devices.

The closure of a key K applies a positive voltage to the lead L and to the line, which voltage, in 35 turn, is conveyed by the line to the potentiometer RR.

It will be noted that the common cathode lead 40 of all of the gas discharge devices T is grounded, thereby setting the potential of the cathode. The positive end of the potentiometer RR is grounded through a line resistor LR. Accordingly, in the absence of a voltage applied to the common lead L by closure of a key K, the positive end of the potentiometer RR is likewise at ground potential, and all of the grids of the tubes T are at 45 potentials more negative than ground, more negative than the cathodes, and more negative than the line.

50 Application of a given positive voltage to the line by closure of one of the keys K raises the potential of the positive end of the potentiometer RR by an amount depending upon the relative resistance of the line and the resistor LR, and bearing the same ratio to the applied voltage, that 55 the resistance of LR bears to the combined resistance of the line plus LR. A fixed percentage of the voltage applied to the line thus appears as a voltage drop across the resistor LR and is available to change the over-all potential of the grids 60 of the tubes T with respect to their cathodes.

In the commercial form of gas discharge device, sold under the trade name, "Thyratron", current flow begins when the grid has approximately the 65 potential of the cathode. In the embodiment shown in Fig. 1, the potentiometer drop between the positive end of the potentiometer RR and the point of connection to the grid of the least negatively biased tube is less than the voltage drop, which will be produced across the resistance LR 70 by the lowest voltage applied to the line by closure of one of the keys K. Thus, when key K1 is closed, a definite voltage, as determined by the potentiometer R, is applied to the line. The voltage drop appearing across the resistor LR 75 then serves to make more positive all of the volt-

ages delivered to the respective grids by the potentiometer RR. This value, upon closure of the key K1, is adjusted to be sufficient to make the grid of the tube T1 positive by a sufficient amount to permit current flow therethrough. This current flow energizes the relay M1, and closes its contacts to actuate any desired device.

Closure of the key K2 impresses upon the line an appropriately higher positive voltage, which 10 voltage produces an increased drop across the resistor LR, the increase being equal to the difference in bias on the grids of the devices T1 and T2. Accordingly, not only is a positive bias applied to the grid of the tube T1, but a positive bias is 15 likewise applied to the tube T2, and both become conducting. Both, therefore, energize their respective relays M1 and M2. However, the initial rapid actuation of the relay M2 opens its lower contacts, thereby interrupting the power supply 20 to the tube T1 and deenergizing the relay M1 before it has completed its full stroke. The relay M2, however, completes its full stroke, closing its upper contacts to perform the functions desired to be produced by the closure of the key K2.

Closure of the key K3 gives a correspondingly 25 still higher voltage drop over the resistor LR, which is adjusted to be sufficiently high to bring the grid of the gas discharge device T3 to the positive condition. Current will then start to flow 30 through the devices T1 to T3. Relay M3 is energized as before indicated for relays M1 and M2 and opens the supply circuit to both devices T1 and T2. As previously described this permits the complete operation of relay M3 to close its upper 35 contacts while deenergizing the relays M1 and M2 before their upper contacts are closed.

Similarly, the closure of the key K4, or the closure of the key K5, will cause the closure only of the desired upper relay contacts of the respective relays, to produce the operations desired by 40 the closure of the keys K4 or K5 by a similar procedure.

Obviously, the number of keys and the number 45 of gas discharge devices is limited only by such factors as the permissible circuit voltages across the keys K, the permissible biases upon the grids of the devices T, and the minimum voltage steps between successive grid biases, and any desired or appropriate number up to the limit set may be 50 utilized. It will be understood that the gas discharge device begins its current conduction at a fairly sharp critical voltage point, but this critical voltage has a small range. The difference in the bias of the successive grids must be 55 substantially greater than this small voltage range. This factor, which is a structural characteristic of the tube is a controlling factor in the closeness of spacing of the taps on the potentiometer RR. In combination with the permissible voltage upon the most strongly negatively biased grid, and the maximum allowable voltage on the devices, which can be utilized, it determines the maximum number of signals which can be transmitted, or the maximum number of operations which can be controlled.

While in the preferred form of the invention just described a particular relay device has been referred to, it is obvious that the invention is operable with any relay device which has a control circuit and a circuit responsive thereto, and which has such an operating characteristic that the controlled circuit passes substantially no current until the control circuit has reached a certain predetermined narrow range of electrical potential, and thereafter the controlled circuit 70 75 80 85 90 95

passes substantially a full predetermined current. In the preferred embodiments of the invention illustrated and described herein the commercially available gas discharge device sold under the trade name "Thyatron" has been used as an example, because it has the above operating characteristic. Discharge devices or electronic tubes having this characteristic are referred to herein as of the "trigger action" type.

10 It will also be apparent that for the purposes of this invention the only "trigger action" essential is one which permits full current to flow suddenly in the controlled circuit when the controlling element reaches the critical potential, irrespective of whether the reverse action takes place or not. If the reverse trigger action does not take place, as is the case with the "Thyatron", then as already described, the controlled circuit may be interrupted by using alternating or periodically interrupted direct current, in which event it interrupts itself when the potential of the control member recedes below the critical value. If a gas discharge device is used in which the reverse trigger action takes place, then obviously to interrupt the controlled circuit it is only necessary to return the control element to the critical value for shutting off the current in the controlled circuit, and uninterrupted direct current may be used in the controlled circuit.

20 In summary, the system of the invention thus provides a plurality of gas discharge devices which, in non-operating positions, carry no current, and which have the grids thereof respectively differently biased, so that the application of positive potential to the system will cause some or all of the grids to assume a potential which will permit current flow through the corresponding devices. Each of the devices has an associated relay adapted to operate contacts to open the anode circuits of all of the devices which have less negatively biased grids. Accordingly, upon the application of a voltage pulse to the system one or more of the devices may start to carry current. However, the quick acting relay opens the anode circuit of all but one of the devices which tend to operate, and, accordingly, but a single one of the associated relays is energized. By this arrangement, it thus becomes possible to cause a single relay to close upon the application of a pulse of predetermined voltage, and to provide thereby for the selective operation of as many other relays as may be desired. Thus, a given relay may be selected by the choice of the magnitude of the voltage pulse applied to the system.

Amplifier combination

The device of the invention may be combined with other devices for the production of other specialized results. In some instances, the permissible maximum voltage, which may be applied to a given line, is limited by the characteristics of the line, and the number of steps of voltage to provide for the desired number of different signals may be such that the difference in voltage between successive steps is less than that required by the system to distinguish accurately between the several signals to be sent.

This invention, therefore, further includes the combination of the plurality of voltage pulse responsive devices, as above described, with an amplifier system adapted to increase proportionally the magnitude of the several voltage pulse signals. This arrangement is particularly shown in Fig. 2, in which there is disclosed a system similar to that of Fig. 1, including the plurality

of keys, gas discharge devices, the associated relays, potentiometers, and grid resistors with connections in general similar to those previously shown. Interposed between the line and the resistor 14 which replaces the line resistor LR of Fig. 1 there is, however, positioned an amplifying system A.

The amplifier A may consist of a single amplifier tube 11, or may consist of a plurality of such tubes, according to the requirements of the system. The line over which the signal current is to be transmitted is connected to the grid of the tube 11, in parallel with the resistor 12, which corresponds to some extent, to the line resistor LR of Fig. 1, in that it causes the application of voltage to the grid of the tube 11 when a key K at the sending point is closed. The resistor 14 is connected in the anode circuit of the tube, and a bias battery C is connected in circuit with the amplifier tube grid.

The system above described is essentially a resistance coupled amplifier system in which the resistors 12 and 14 correspond in general to the line resistor LR of Fig. 1, but the interposed vacuum tube causes an increase in the electrical magnitude of the voltage applied across the resistor 14. A direct coupled amplifier is desirable in systems in which random or low frequency pulses are to be amplified and is convenient for any frequency. However, in systems in which a rapid sequence of pulses is to be transmitted, as may occur with high speed telegraphy, satisfactory results may be obtained by the use of an amplifier in which the coupling between successive stages, the input line, and the voltage responsive devices, is obtained by inductive or transformer coupling, or by capacitive or condenser coupling. These latter forms of coupling, however, are useful only in the event that the signal pulse occurs at a relatively rapid rate, since such amplifiers do not normally function for the amplification of sustained steady values.

In this embodiment, the positive pulses delivered by the keys K, produce a voltage drop across the resistance 12. The bias battery C is desirably of such a voltage as to nearly block the tube 11, allowing substantially no current to flow therein, and in the resistance 14, in the absence of signals. Upon the arrival of the positive pulses from the keys K, the grid of the tube 11 is made less negative, allowing current to flow in the tubes 11 and the resistance 14, thereby delivering amplified positive pulses to the potentiometer RR and the gas discharge device. These amplified voltage pulses then produce therein similar reaction to those described in connection with Fig. 1.

The system above disclosed is particularly advantageous in connection with cable signaling devices, as is also shown in Fig. 2. In this embodiment, a similar form of sending system may be utilized to that shown in Fig. 1, consisting of a plurality of keys K, and a similar potentiometer R, energized by a suitable source of current, as a battery B. The variable voltage pulses are applied to the cable as shown, and conveyed therethrough to the amplifier A, by which they are increased proportionately in electrical magnitude to a desired value and applied to the resistor 14, corresponding to the line resistor LR of Fig. 1. The voltage drop in the resistor 14 from the plate current in the tube 11 changes the effective potential upon the potentiometer, RR, and one or more of the tubes T tend to

carry current as before described, and, as before, only that tube highest in sequence has its relay operated, the lower relays in the sequence being put out of operation by the opening of the supply contacts in the highest energized tube relay.

For short cables, no particular precautions are necessary for the operation of the selector device at the remote end. For longer cables, in which the capacitance and resistance become significant factors in the shaping of signal pulses, through their influence on the growth and decay of signal pulses, various means may advantageously be utilized, as is well known to workers in the art, for the reshaping and modifying of the signal pulses, and the response of the selector system thereto, including such modifications as the use of "loaded" cables, special methods of current supply, timing of the several responses of the devices to obtain a particular pulse shape, and many other steps of procedure, which will be obvious.

It may be noted that, in the system above described, each signal is represented by but a single pulse and, accordingly, a substantial gain in speed is obtainable over the ordinary signaling methods in which a plurality of pulses is required for most signals representing the respective characters. This feature is of especial value in cable signaling, because of the time required for the growth and decay of the successive signal pulses, which, under ordinary signaling conditions, limits the cable speed.

Teletypewriter

This system is of particular advantage for the operation of devices such as the teletypewriter over a cable line, as well as over the usual land line. The fact that, but a single pulse is required for any one of a large number of different signals or characters makes it possible to operate such a teletypewriter by means of a single pulse system, as distinguished from the present type of operation in which a plurality of pulses such as those of the five unit code is required for the production of a single character on the teletypewriter. This system thus permits a higher speed of operation of the teletypewriter.

As shown in Fig. 2, each key lever of the typewriter may be equipped with a solenoid, or other operating means, adapted to pull the key lever downward and actuate the type bar in the required manner when the corresponding solenoid, or operating means, is energized. While Fig. 2 shows but five gas discharge devices T, any required number may be utilized and, if desired, one for each key of a standard typewriter, including the shift key. The control of the shift key may take any desired one of a number of different forms, which will be obvious to those skilled in the art, such as a shift key with a mechanical lock, and separate unshift or shift-release key, respectively controlled by separate gas discharge devices T and associated relays. The keys K may also be combined with those of a standard typewriter to cause the production of the same typing at both the sending and receiving end, or the keys K may be simply circuit closing keys without attached typewriting mechanisms. In the latter event, of course, no record of the message is produced at the sending end.

Alternative relay form

Fig. 2 shows an alternative form of relays associated with the tubes T. In this form each tube T has connected thereto, two relays, one of which

is quick acting, the other somewhat delayed in its action. Convenient commercially available relays of the telephone type may be utilized for this purpose. The quick acting one may be of a type which opens its contacts in about two-thousandths of a second, and the slower acting one of a type which operates its contacts in approximately thirty-thousandths of a second. The exact speed of operation of these relays may be chosen according to the character of the associated line and the wave form of the signal pulse.

In the event that the associated line is short and the growth of the current rapid, any convenient rapid acting relay may be utilized for the first relay, and the second relay may be any convenient one which operates a trifle more slowly. In the event that the associated lines are long, and, for that or any other reason, the growth of the current is slow, it is desirable that the time of action of the second relay should be greater than the time of action of the first relay, by an amount at least equal to the length of time necessary for the maximum pulse to be received to grow to a predetermined portion of its final value, or to its final value. It will be observed that in the embodiment of Fig. 2, the rapidly operating relays N are connected directly in the anode circuits of the respective devices with the condensers C, as in the embodiment of Fig. 1, and that the relays N have two pairs of contacts, one pair being adapted to close the circuit of the slower acting associated relay O and the other being adapted to open the supply lines to all of the anodes of the devices T lower in the grid bias sequence. The circuit is broadly the same as the circuit of Fig. 1, the difference being that the two relays are used with each gas discharge device adapted respectively to operate the quick acting and slow acting contacts, instead of making a single relay winding serve for the operation of both a quick acting and a slow acting set of contacts. This embodiment is convenient because of the fact that such commercial relays are readily available, whereas the relays suggested in Fig. 1 must be especially designed.

Alternately, the relays N and O may be connected in parallel or in series instead of in cascade. In such an embodiment the relay N need have only one set of contacts, namely, that required to break the anode supply circuit to devices lower in the grid bias series. Also, in that embodiment, the relay O may perform its function by direct mechanical action, or by opening or closing such circuit contacts as desired.

By the devices of Fig. 2 there is thus produced an embodiment adapted for use over long lines, cables, or other complicated circuits, which utilizes standard commercial parts for its assemblage, and which is adapted to the operation of a teletypewriter by a particularly simple and convenient mechanism. The embodiment as above described is adapted to operation singly over a cable. It is equally well adapted to various systems of multiplex operation. The various circuits and systems of multiplex operation are well known to those skilled in the art and need not be here described, and the manner in which the system of this invention may be applied to them will be apparent from the description already given.

Radio transmission

The system is equally adapted to cooperation with a radio channel. Such an adaptation of the present invention is shown in Fig. 3, in which

figure there is outlined a radio transmitting system adapted to transmit radio signals modulated in amplitude according to the relative voltage delivered thereto from the keys K, and a receiving set responsive to signals received from the sending set, adapted to deliver electrical pulses of differing magnitudes according to the amplitude of the received radio signals.

A plurality of keys K are provided as in the embodiment of Fig. 1, and are associated with a potentiometer, R, which is energized by a power supply B, as before described. Closure of any one of the keys K delivers a voltage pulse of corresponding magnitude to the radio transmitting apparatus.

The transmitting apparatus, oscillating system, and modulating system, may be of the simple form shown, or may be the well known Heising constant current form of modulation, or any other suitable form of those well known to workers in the radio art. The voltage pulse may be amplified before it is caused to modulate the high frequency oscillations by an amplifier of the type shown in Fig. 2, if the signal strength to be transmitted makes amplification desirable. Obviously the coupling between successive amplifying stages and between the amplifier and modulator circuit must be adapted to the type of pulse to be amplified. If these pulses are of low or random frequency, a direct coupled or resistance coupled amplifier is desirable. If they occur at relatively rapid rates a capacitive or inductive type of coupling, as previously suggested, may be utilized. Also, the signal may be amplified at radio frequency after modulation. In any event, the system required is one which will convert voltage pulses of different magnitudes into radio frequency oscillations of corresponding amplitude.

The receiving member may be of any convenient type of radio frequency receiver, which may include amplifier members for amplification at radio frequency, and an output detector or rectifier. The output device is desirably associated with an output resistance corresponding to the line resistance LR of Fig. 1, by which a varying amplitude of high frequency signal applied to the detector device produces a proportionate unidirectional voltage pulse in the form of a voltage drop across the output resistance. This voltage drop across the output resistance may be amplified, as shown in Fig. 2, or may be utilized directly for the operation of the selector device corresponding to that shown in Fig. 1.

By this embodiment of the invention, the desired signal originating as a voltage pulse may be converted to a high frequency oscillation of corresponding amplitude, transmitted over a radio channel, received at a remote point, detected or rectified, reconverted to a corresponding voltage pulse and applied as a voltage pulse to the voltage responsive member of the invention to cause the selective operation of a predetermined gas discharge device and the predetermined operation of a single relay assembly for the production of a predetermined signal, or a predetermined operation as previously described.

Telephone pulsing

The system of this invention is conveniently applicable to the transmission of automatic telephone control signals. For this purpose a device may be provided at a subscriber's station, or at a telephone exchange, adapted to send single electrical pulses of a magnitude varying accord-

ing to the digit to be indicated. These pulses may be received at a central exchange or branch exchange and utilized to control the selection of the called subscriber. For this purpose a device similar to the receiving portion of Fig. 1 or Fig. 2 may be utilized with such changes as are necessary for the purpose, which will be indicated in the following description. This device may take any one of many forms, which will be obvious to those skilled in the art, its basic usefulness depending on the fact that it will close any selected one of ten or more line, or trunk selecting, circuits.

Referring to Fig. 4, the subscriber's instrument may consist of the usual call bells 21, condenser 22, induction coil 23, receiver 24, transmitter 25, and hook switch 26. These may be connected in any one of the usual ways, as, for instance, in the manner shown, which is very commonly used. In addition to the usual equipment there is also provided a plurality of push buttons 31, 32, 33, etc. In the drawings, for the sake of simplicity only five of these are shown to illustrate the principle. In practice any convenient number may be employed, as, for instance, ten, for operation in the decimal system of numbering. There is also provided an extra pair of contacts 27 and 28, on the hook switch adapted to close a circuit when the receiver is raised.

Associated with the push button is a resistance SR, tapped at as many points as there are push buttons, 21, 22, 23, etc., the points preferably having equal resistances between them. This resistance should preferably be quite high in comparison to the line resistance. One end of this resistance is permanently grounded, as shown.

With none of the push buttons depressed, one wire B of the subscriber's line goes directly to the receiver, transmitter, etc., while the other wire G goes through contacts on each button connected in series, and, finally, also to the receiver, transmitter, etc.

It is to be noted that the wire B that goes directly to instrument is the one which is connected to the positive side of the common battery CB at the telephone exchange, and the system requires that the negative side of this battery be grounded. The other wire G is ultimately connected to ground at the exchange.

When the receiver is lifted from the hook, the hook switch, through the springs 27 and 28, completes a circuit from the battery side of the line to the push buttons, as shown. This makes the push buttons inoperable unless the receiver is off the hook. When one of the buttons 21, 22, 23, etc., is depressed, the right hand springs connect the ungrounded end of the resistance SR to the battery side of the line, through springs 27 and 28. In this position the exchange battery, the battery side of the subscriber's line, and the resistance SR, cooperate to form a simple potentiometer circuit, the resistance being bridged across the battery by having one of its terminals connected to the positive side of the battery through the line wire B, while its other terminal is connected to the negative side of the exchange battery through their common connection to ground. The left hand springs of the depressed button disconnect the line wire G from the instrument and connect it to one of the taps of the resistance SR, a different tap being associated with each button. The wire G, therefore, becomes the variable potential member of the potentiometer and carries back to the exchange a potential depending on the button pressed. It

is to be noted that the left hand springs of the push buttons are of the "make before break" type, so that the operation of any push button does not break the line circuit once it is established by removing the receiver from the hook. The necessity for this will appear later.

The net result of the scheme of connections shown and described is that it provides a conventional type of subscriber's circuit when no 10 button is pressed. When the receiver is lifted off the hook and a button is pressed, the telephone instrument proper is disconnected from the line, while the resistance associated with the push buttons is converted to a potentiometer, 15 fed from the central office battery over one of the line wires with ground return. The other line wire serves as the variable potential lead from the potentiometer and carries back to the central office a potential depending upon the button pressed, within the limits of the central office battery. This part of the apparatus is, 20 therefore, a counterpart of the sending keys, associated potentiometers, etc., shown in Figs. 1, 2 and 3, in other embodiments of the invention.

25 At the central office or sub-station, the two line wires pass through a chain of contacts of the selector relays O in the manner shown. The side of the line which feeds the potentiometer in the subscriber's instrument then goes to 30 the positive side of a source of direct current, which may conveniently be the central office common battery, the negative side of this battery (or other source) being grounded. The other line wire terminates at a resistance LR, the other 35 terminal of which is grounded. This resistor is similar in function to the resistance LR of Figs. 1 and 2.

Connected to the same terminal LR with the line wire is a potentiometer RR, which is the 40 same in function and purpose as the similarly lettered potentiometers of Figs. 1 and 2. It puts successively larger negative biases on the grids of the tubes T31, T32, T33, T34, T35 and T36.

45 It is to be noted that the number of tubes is one greater than the number of push buttons, and that the tube having the highest negative bias has alternating current supplied to its anode. All the rest of the tubes are supplied with direct current anode power, which, for convenience, is 50 shown as coming from the common battery CB of the exchange. This anode supply of direct current passes through "make contacts" of a relay 30, placed in the G side of the subscriber's line, the purpose of which will presently appear. 55 The relay 30 is shunted by a condenser to reduce the line impedance to voice currents.

The manner of operation of the apparatus is as follows: When the receiver is lifted from the hook, a circuit is formed from the positive side 60 of the battery CB, through the B side of the subscriber's line, through the G side of the line, through LR and back to ground. This completes the circuit, since the negative side of CB is grounded. 65 The resistance of LR is so high that it constitutes by far the greatest part of the resistance of this entire circuit, hence, almost the full voltage of the battery CB appears as a drop across LR. This is sufficient to overcome the bias of the 70 entire chain of tubes T, including T36, which has the highest bias in the chain. This permits current to flow through all the tubes and their associated relays N, which are quick acting and correspond to the quick acting relays N of Fig. 2. 75 However, one set of contacts of the relay N36

interrupts the anode current for all the lower biased tubes in the chain, as already described, and prevents the operation of all the relays N (except, of course, N36). The other set of contacts of N36 passes current through the slow acting relay O36, which corresponds to the relays O of Fig. 2. This relay now pulls up, connecting to the line the "tone" circuit. This tone circuit sends out over the line the well known dialing tone, indicating that the line is ready for use. 10 In the event that this apparatus should be used in connection with an automatic line finder or selector switch of the type now in use, this feature would be particularly desirable, as it would cause the subscriber to wait until the line finder 15 had operated, before operating a push button.

When the subscriber hears the "ready tone", he pushes a button corresponding to the first digit of the number he desires, for example, the button 34. This disconnects the instrument 20 from the line and puts on the wire G a corresponding potential which is lower than that existing when the instrument was across the line. This lower potential is insufficient to overcome the bias of tube T36. This tube, being supplied 25 with alternating current therefore ceases to conduct current at the next half cycle when the anode becomes negative. This causes the armature of relay N36 to drop back, the relay reconnecting the direct current to the anodes of the 30 preceding tubes T.

By the method already described, the relay N34 corresponding to the button 34 now pulls up and permits the complete operation of its associated slow acting relay O34. The closing of 35 relay O34 connects the subscriber's line to the corresponding selected line L34, which may be directly the line of the called subscriber, or which may merely lead to a group of lines or trunks from which further selection may be made by 40 again pressing one of the buttons 31, 32, etc., accordingly, to the next digit of the number to be selected.

Since the tubes T (except T36) are supplied 45 with direct current at the anodes, the re-establishment of the negative bias on their grids does not interrupt the anode current; hence, the selected relay (N34 in this case) remains energized after the corresponding button is restored to its 50 normal position.

The operation of any of the relays O also connects to the subscriber's line the repeating coil, 41, which, through its connection to the battery CB, furnishes the proper current to the line for energizing the called and calling subscribers' instruments. This repeating coil need be connected to the contacts of the relays O, however, only if these relays are used to select subscribers' lines, that is, if they respond to the final digit of the called number. If the relays O are used for intermediate digits, the coil 41 and the corresponding contacts of the relays O may be omitted. By this arrangement only one repeating coil will supply current to the line, and that coil will be connected at the selector relay of the last digit in 65 the number.

It will be noted that the anode current for the tubes T comes through a contact of the relay 30, which is connected in series in the subscriber's line, and so arranged that the tubes T are supplied with anode current only when the relay 30 is energized. It has also already been pointed out that the buttons 31, 32, etc., have "make-before-break" contacts, hence, the pressing of any of these buttons does not even momentarily open the 75

line circuit, but merely changes the potential of the line wire G with respect to ground. The relay 30, therefore, continues energized throughout all the operation of the buttons, as long as the receiver is off the hook. When the conversation is completed and the receiver is restored to the hook, the relay 30 is de-energized, the supply of anode current to the tubes T (except T36) is interrupted, the relays N and O are de-energized, 10 and the apparatus returns to the original condition, ready for operation once more.

The relay 30 must be sensitive to very small current, to operate in series with the resistance LR. Relays operable on very small currents are, however, commercially available, or the relay may conveniently be replaced by a suitable potential operated device, such as a vacuum discharge or gas discharge tube. As already explained, the line G is at ground potential only when the receiver is on the hook, and thereafter is continually at some potential higher than ground. The grid of a triode may, therefore, be connected to the line wire G in place of the relay 30, and the change of potential thereon utilized to operate a relay in the anode circuit, this relay then performing the function indicated as performed by relay 30.

It will also be apparent that in the above described embodiment, if each of the lines L31, L32, 30 L33, etc., lead to another selector circuit, then, if one of the buttons 31, 32 etc., is held down too long, it may also operate a selecting relay O in the next selector circuit, thereby causing an error. To obviate this, each successive selector circuit 35 after the first may be provided with a device, which will keep it disconnected from its corresponding resistance LR, such as contacts on an appropriate relay, until after the line wire G has attained its highest potential, which occurs when none of the buttons are depressed and only 40 the instrument is across the line. With this arrangement the pressing of a button once will then operate only one selector relay no matter how long the button may be kept depressed. To operate the next selector relay in the chain, corresponding to the next digit in the number, it 45 will be necessary to let each button come back to normal before pressing it, or another button, again. This action restores the highest available potential to line wire G, and permits the resistor LR of the circuit last selected to be connected to that circuit. Means for causing each successive selector circuit to remain disconnected from its 50 resistance LR until after the line wire G has attained a certain fixed potential, are readily available and will suggest themselves to those skilled in the art, and need not be here described.

The purpose of the foregoing description, relating to telephone signaling, has not been to show a finished system of automatic telephony, complete in every detail, but merely to outline the broad general principles along which the present invention can be applied to automatic telephony. Such details as the busy test, the selection of non-busy trunks, the specific changes necessary for 55 party-line ringing, etc., will be obvious to those skilled in the art, and the means of accomplishing these results need not differ greatly from means already employed with the systems now in use, and suitable circuits and devices for these purposes will be obvious.

It will also be obvious to those skilled in the art that alternate methods may be used other than those suggested, without departing from the spirit of the invention. As an example, the potentiometer at the subscriber's instrument may

be powered by a local battery, the system may be used in a local battery or magneto exchange, or it may be used with particular advantage over long distance lines, with or without a common battery at the exchange.

Thus, the system of the invention may be used to enable a subscriber, by suitable operations at his instrument, to select any one of a considerable number of lines leading to other exchanges or sub-exchanges, groups of lines, individual lines, 10 or selected means of ringing individual lines, and to repeat this selection successively to effect the final selection of a single line, and means of ringing any party on that line, out of an entire telephone system. 15

Light responsive system

The basic elements of the invention described with Fig. 1 may be utilized in combination with a photo-cell system for other useful functions. 20 A photo-cell is responsive to light, permitting a flow of electrical current therethrough, which is proportional to the illumination, a high illumination producing a larger current flow than a lesser illumination. When it is desired to obtain responses in steps, depending upon the degree of illumination, the embodiment of Fig. 5 may be utilized. As indicated, the photo-cell, which may be of the emission type, photo-galvanic type, or photo-resistor type, is connected, as shown, to an 30 amplifier. As already explained in other embodiments of this invention, it is desirable that this amplifier be of the direct coupled type in order that it may faithfully amplify sustained current or voltage pulses, or pulses of random duration. Where the application is such that the pulses will be sufficiently frequent and regular, then inductively and capacitively coupled amplifiers may be used. The output of this 35 amplifier is connected to the resistor LR, corresponding to the line resistor LR of Fig. 1. The gas discharge devices of Fig. 1 are provided, as indicated, by a box marked "selector" shown in Fig. 5, and operated in a similar manner to close a 40 circuit through the respective pairs of leads from the selector as indicated. 45

By this embodiment of the invention, a given degree of illumination on the photo-cell causes a corresponding current flow therethrough, which is amplified and caused to yield a suitable voltage drop over the resistance LR, which, in turn, causes the actuation of one of the gas discharge devices T, as shown in Fig. 1, and the actuation of the corresponding relay to close a circuit to the desired operable device. A higher degree of 55 illumination produces a higher current flow through the resistor LR and closure of the corresponding relays to operate another control device.

This embodiment of the invention is particularly adapted to the sorting of objects of different shades, or light reflecting, or transmitting power, or color. Light from the sortable objects may be caused to impinge on the photo-cell, to cause the corresponding current flow therein. This 60 current flow produces a voltage drop in the resistor LR, which causes the appropriate relay T to operate and close its contacts. Closure of contacts may then be used to produce any desired 65 operation, such as the selection of sorting pockets. This sorting operation may be conducted according to the reflecting power of the object, or according to its optical density, its light transmissive power or according to the presence, or absence, or size of openings therein. 70 75

Alternatively, the device may be utilized for the control of various members according to the intensity of illumination, such as the turning on and off of successive steps of artificial illumination, as the natural light in a given place varies, or such as the control of window shades, etc. It may be noted that this device is one of the few available devices which are adapted to respond to definite discrete steps over the range of a continuous change of illumination, and that it responds in successive steps to the exciting energy changes.

Remote control

Many other uses of the system of this invention will be obvious, among which may be mentioned the use of the system in duplicate for remote control operation over a single line, of electrical switches at a sub-station or unattended generating station from a main load dispatch center with automatic answer back, upon the occurrence of changes at the remote point, the control of selected mechanical operations from a distance, such as the opening of selected chutes or outlets, etc., or the opening of valves in piping systems, the throwing of switches of various sorts and many other uses, which will occur to those skilled in the art.

The device of this invention thus provides simple means for the transmission of signals by single electrical pulses of differing electrical magnitude, primarily differing in voltage, but significantly differing in current, since differing currents are readily converted into different voltages by the differing drops they produce along the resistances. The responses to these different voltages may be utilized independently for the control of a plurality of different predetermined and selected operations, which operations are performed independently in response to initiating pulses in which the significant factor is electrical magnitude rather than the time duration, as is necessary for most signal impulses of the prior art.

Also since the general term "gas discharge device" has been used heretofore to designate some electronic devices which do not possess the operating characteristics previously referred to, the term "gas discharge device of the trigger action type", wherever it occurs in the claims appended hereto, shall be taken to mean an electronic or gas discharge device having a controlled circuit responsive to a controlling element and having the operating characteristic that the controlled circuit passes substantially no current until the control element reaches a certain narrow predetermined range of electrical potentials and passes substantially a predetermined current when the control element reaches or exceeds this range of potentials, further increases in the potential of the control element being substantially without effect on the magnitude of the current in the controlled circuit.

While there are disclosed but a limited number of embodiments, the invention is adapted to the production of still other embodiments without departure from the inventive concepts herein disclosed, and it, therefore, is requested that only such limitations be imposed upon the appended claims as are stated therein or required by the prior art.

The invention claimed is:

1. An electrical signaling system comprising means for sending a plurality of significant pulses of different electrical magnitudes, and means se-

lectively responsive thereto according to the electrical magnitude for the production of predetermined responses, said last mentioned means comprising gas discharge devices of the trigger action type.

2. An electrical signaling system, comprising, in combination, means for sending electrical pulses of non-significant time duration and significant electrical magnitude, and means selectively responsive to the electrical magnitude of the signal, said last mentioned means comprising gas discharge devices of the trigger action type.

3. An electrical system comprising means for the production of electrical pulses of different electrical magnitudes, means for the conveyance thereof to a remote point, and means selectively responsive to the electrical magnitude for the production of a predetermined response, said last mentioned means comprising gas discharge devices of the trigger action type.

4. In combination, a plurality of circuit members respectively adapted to apply different electrical voltages to a common circuit, a plurality of gas discharge devices of the trigger action type connected in parallel to said circuit respectively responsive to different applied voltages thereon, and means actuated thereby for the production of a predetermined response and for preventing a response by devices actuatable by lower voltages than the predetermined voltages.

5. The combination of a plurality of gas discharge devices of the trigger action type, means for normally applying different biases to the grids thereof, means responsive to current flow in said devices, and means for varying the potential of the bias producing means for overcoming the grid biases of said devices.

6. In combination, a plurality of gas discharge devices of the trigger action type having grids, and anodes, means for applying different normal grid biases to the respective grids thereof, means for overcoming the grid bias of said devices, and means for causing only one thereof to pass current for the energization of a given indicating device.

7. In combination, a plurality of gas discharge devices of the trigger action type having grids, relay members actuated thereby, means for normally applying different grid biases to the respective grids thereof, means for overcoming the grid bias of a plurality of said devices, and means for preventing the response of the devices having lower grid biases.

8. In combination, means for initiating a plurality of electrical pulses of differing magnitude, means for conveying such pulses to a remote point, a plurality of gas discharge devices of the trigger action type at the remote point respectively independently responsive to a predetermined signal pulse magnitude, and members actuated by the response of said gas discharge devices.

9. In combination, a signal sending mechanism comprising a potentiometer and a plurality of associated keys, a signal conveying channel and a signal responsive member comprising a plurality of normally differently biased gas discharge devices of the trigger action type respectively responsive to different signal voltage magnitudes, means for preventing the operation of more than a single one of the group of gas discharge devices, and means for causing an operation in response to the operations of the selected gas discharge devices.

10. In combination, means for initiating signal pulses of varying electrical magnitude, means for

converting said pulses into oscillations of corresponding amplitude, means for receiving said oscillations, means for detecting said oscillations and producing voltages corresponding to 5 those initiating said oscillations, and means responsive to the voltage impulses therefrom to cause the operation of any one only of a group of gas discharge devices of the trigger action type, and the production of a predetermined operation thereby.

11. In combination, a group of gas discharge devices of the trigger action type having grids, means for producing a plurality of different biasing voltages connected to said grids, relays associated with said gas discharge devices operable by current flow therethrough, and means for varying the potential of said bias producing means with respect to the cathode of said gas discharge devices, said last mentioned means comprising a controllable voltage source.

12. In combination, a group of gas discharge devices of the trigger action type having grids, means for producing a plurality of normally different biasing voltages connected to said grids, 15 relays associated with said gas discharge devices operable by current flow therethrough, means for varying the potential of said bias producing members with respect to the cathodes of said gas discharge devices, said last mentioned means comprising a controllable voltage source, means 20 for preventing the operation of more than one of the gas discharge devices, and means operable by said discharge devices for producing a given response.

13. In combination, a plurality of gas discharge devices of the trigger action type, a member adapted to supply differing grid voltages to the several devices whereby the several devices are 25 differently biased negatively, and means for supplying varying amounts of positive potentials to the biasing devices to convert the biases upon 30 some of the grids from negative to positive values.

14. In combination, a plurality of gas discharge devices of the trigger action type, a member 35 adapted to supply differing grid voltages to the several devices whereby the several devices are normally differently biased negatively, means for supplying varying amounts of positive potentials to the biasing devices to convert the biases upon 40 some of the grids from negative to positive values whereby current is allowed to flow therein, relay 45 means responsive to current flow in said tubes, and means operable by said relay for producing suitable responses and preventing the flow of current through more than one gas discharge device.

15. In combination, means for producing signal pulses of varying magnitude, means for amplifying the magnitude thereof, and means responsive 50 in steps to the amplified magnitude to produce a response according to the magnitude of the original voltage pulses, said last mentioned means comprising gas discharge devices of the trigger action type.

16. In combination, a photo-cell member responsive to changes in illumination, and a device comprising a plurality of gas discharge devices of the trigger action type and respectively associated relays responsive individually in successive 55 steps to the changes in illumination upon said photo-cell, said relays being adapted to be operated thereby for the production of other responses.

17. In combination, means for initiating electrical pulses corresponding to intelligible char-

acters, each character being represented by a single pulse of a different electrical magnitude from those representing other characters, means for conveying said pulses to a remote point, a system comprising a plurality of members respectively responsive to pulses of differing magnitudes, combined with means for preventing the operation of more than one device in response to a given pulse, and means actuated thereby for the recording of the various characters indicated 10 by the pulses.

18. In combination, means for initiating electrical pulses corresponding to intelligible characters, each character being represented by a single pulse of a different electrical magnitude 15 from those representing other characters, means for conveying said pulses to a remote point, comprising a cable system and means for controlling the pulse form, a system comprising a plurality of members respectively responsive to pulses of 20 differing magnitudes, combined with means for preventing the operation of more than one device in response to a given pulse, and means actuated thereby for the recording of the various characters indicated by the pulses.

19. In combination, means for initiating electrical pulses indicating by the electrical magnitude thereof the several numerical digits, means responsive thereto for determining the digit indicated comprising a plurality of gas discharge 30 devices of the trigger action type and associated relays, and means actuated for selecting and connecting a predetermined numbered circuit.

20. An electrical signaling system, comprising, in combination, means for sending electrical 35 pulses of non-significant time duration and significant electrical magnitudes, and means selectively responsive thereto, said last mentioned means including gas discharge devices of the trigger action type responsive to all the pulse values 40 above a critical value different for each device and mechanism associated with each device for the production of a usable response and the prevention of response by a member having a lower critical value.

21. In combination, a plurality of gas discharge devices of the trigger action type having grids, individual means controlled by current flow in each of said devices, means for normally applying different grid biases to the respective grids 50 of said devices, means for overcoming the grid bias of a group of said devices, and means for preventing the actuation of the first mentioned means of all the devices of said group except the one most negatively biased.

22. In combination, a plurality of gas discharge devices of the trigger action type having grids, means responsive to current flow in said devices, means for normally applying different grid biases to the respective grids of said devices, means for 60 overcoming the normal grid biases of a plurality of said devices, and means controlled by the passage of current through one of said devices for preventing the passage of current through the others.

23. In combination, a plurality of gas discharge devices of the trigger action type having grids, individual means controlled by current flow in each of said devices, means for normally applying different negative grid biases to the respective grids of said devices, means for overcoming the negative grid biases of a group of said devices, and means controlled by the passage of current 70 through the device of highest negative grid bias which has been overcome for preventing the 75

passage of current through the devices of lower grid bias.

24. In combination, a plurality of gas discharge devices of the trigger action type having grids, 5 means responsive to current flow in the plate circuit of said devices, means for normally applying different negative grid bias to the respective grids of said devices, means for overcoming the negative grid bias of a plurality of said devices, 10 and means controlled by the current flow in the device of highest negative grid bias overcome for opening the plate circuit of the devices having lower grid biases.
25. In combination, a plurality of gas discharge 15 devices of the trigger action type having grids, slow acting relays for producing a desired response controlled by current flow in the plate circuits of said devices, means for applying different negative grid bias to the respective grids 20 of said devices, means for overcoming the negative grid bias of a plurality of said devices, and

fast acting relays controlled by current flow in the plate circuits of said devices for opening the plate circuits of the devices having lower grid biases.

26. In combination, means for initiating electrical pulses corresponding to intelligible characters, each character being represented by a single pulse of different electrical magnitude from those representing other characters, means for conveying said pulses to a remote point, said last 10 mentioned means comprising a cable system and means for controlling the pulse form, a system comprising a plurality of gas discharge devices of the trigger action type respectively responsive to pulses of different magnitude combined with 15 means for preventing the operation of more than one device in response to a given pulse, and means actuated thereby for indicating the various characters indicated by the pulses. 20

MAURICE D. SARBEY.
